UNITED STATES PATENT OFFICE.

WILLIAM PRINCE-SMITH AND JAMES ROBINSON, OF KEIGHLEY, ENGLAND.

SPINDLE OF FLIER SPINNING, ROVING, AND ANALOGOUS MACHINES.

Application filed August 26, 1926, Serial No. 131,728, and in Great Britain November 21, 1925.

This invention relates to flier-spinning, roving and analogous machines, having spindles which are carried by footstep bearings and are provided with intermediate 5 bearings offering lateral support, the fliers being attached to the heads of the spindles.

In machines of this type trouble is often experienced at high speeds, owing to the vibration arising therefrom, and this invention has for its object to secure steadier running of the spindles at normal speed as well as to enable a greater spindle speed to be obtained without excessive vibration.

Accordingly, the invention consists in 15 providing a flier-spinning, roving or analogous machine of the type referred to with overhead means offering support to the tops of the fliers during the spinning, roving or other operation, and means for withdrawing such support in order to permit the doffing operation to be performed.

Two convenient constructional forms of the invention are illustrated by way of example in the accompanying drawings, in 25 which Figure 1 is a sectional elevation of part of the upper portion of a flier roving machine, and Figure 2 is a plan view of part of the overhead rail showing a modified form of slot therein and a correspondingly slotted bush. Figure 3 is a front view of part of the upper portion of a machine and Figures 4 and 5 are a sectional elevation and plan view, respectively, embodying an alternative design to that indicated by Figures 1 and 2.

Referring to Figure 1, A is an overhead rail located above the tops of the fliers B and formed with apertures C at intervals corresponding with the pitch of the fliers, 40 in each of which apertures C is fitted non-rotatably a flanged bush D adapted to serve as a bearing affording lateral support to the upwardly projecting neck E of the flier; the spindles (not shown) in this case being supported at their lower extremities.

The rail A is supported at intervals by the forwardly and horizontally disposed carrier members F which are secured to the heads of downwardly extending vertical stems G adapted to slide in guide brackets H bolted or otherwise suitably secured to the top rail or beam J of the machine.

Below said stems G and extending longitudinally of the machine is a rock shaft K 55 upon which are keyed cams or eccentrics L, one below each stem G, which when the

shaft K is rocked, contact with the lower extremities of said stems and displace them vertically upwards prior to the performance of the doffing operation. In their upward

movement said stems raise the members F and hence also the rail A and resultantly withdraw the flanged bushes or bearings D clear of the necks E of the fliers which are then manipulated together with the spindles

to doff the bobbins. In this construction if the spindles are moved angularly forward to effect the doffing of the bobbins the thread is drawn through the bore of each

bush D, but, as shown in Figure 2, the apertures C in the rail A may be slotted radially as at C' and the bushes D may be correspondingly slotted radially as at D' in order to enable the thread to pass clear of the bushes and rail when the spindles are moved

to doff. During the spinning operation the lateral support afforded by the bushes or bearings D to the necks of the fliers materially decreases vibration at high speeds and enables the spindles to be run at greater velocity than heretofore without detriment to the machine and without increased vibration.

Referring now to Figures 3, 4, and 5, each of the apertures C² in the rail A' is rebated or stepped in formation, the smaller diameter being uppermost, and each of the bushes D² is correspondingly stepped externally and is held against rotation by means of a pin M which contacts with the head of a set screw N screwed into the underside of the rail A'.

In this case instead of withdrawing the bushes D² from the necks of the fliers the rail A is raised clear of the bushes each of which is retained in position upon the neck E' of its corresponding flier by means of a split ring or collar O sprung over and embracing said neck E' on top of the bush D².

The rail A' is supported on vertically movable members F', G', sliding in guide brackets H' bolted to the beam J' cams or eccentrics L' on camshaft K' actuating the stems G'.

This construction of stepped bush and aperture is found to enhance the steadiness of the spindle mounting at high spindle speeds.

We claim:

1. In flier-spinning, twisting, roving and analogous machines, overhead means offering support to the tops of the fliers during the

spinning, roving or other operation, and means for withdrawing said support in order to permit said spindles to be doffed.

2. In flier-spinning, twisting, roving and analogous machines, an overhead rail apertured correspondingly with the spacing of the spindles, bearing bushes fitting said apertured rail and engaging the tops of said fliers, and means for raising said overhead rail in order to permit said spindles to be doffed.

3. In flier-spinning, twisting, roving and analogous machines, an overhead rail apertured correspondingly with the spacing of the spindles, bearing bushes fitting said apertured rail and engaging the tops of said fliers, carrier members supporting said overhead rail, said carrier members being mounted slidably in a vertical direction, and means for raising said carrier members and said overhead rail in order to permit said spindles to be doffed.

4. In flier-spinning, twisting, roving and analogous machines, an overhead rail apertured correspondingly with the spacing of the spindles, said overhead rail affording lateral support to said fliers during the spinning operation, bearing bushes fitting in said

apertured rail and engaging the tops of said fliers, substantially right-angled carrier members supporting said overhead rail, said substantially right-angled carrier members being mounted to slide vertically and means for raising said substantially right-angled carrier members and said overhead rail at appropriate times for the purpose specified.

5. In flier-spinning, twisting, roving and analogous machines, an overhead rail apertured correspondingly with the spacing of the spindles, said overhead rail affording lateral support to said fliers during the spinning operation, bearing bushes fitting in said apertured rail and engaging the tops of said fliers, substantially right-angled carrier members supporting said overhead rail, said substantially right-angled carrier members being mounted to slide vertically, and cam operated elevating mechanism co-acting with said substantially right-angled carrier members and said overhead rail at appropriate times for the purpose specified.

In testimony whereof we affix our signatures.

WILLIAM PRINCE-SMITH.
JAMES ROBINSON.
